DESIGN FOR A COMBINED FOLDING DOLL HOUSE AND YARD

Ellsworth E. Saxton, Seattle, Wash.

Application September 25, 1934, Serial No. 53,393

Term of patent 3½ years

To all whom it may concern:

Be it known that I, Ellsworth E. Saxton, a citizen of the United States of America, residing at Seattle, in the county of King and State of Washington, have invented a new, original, and ornamental Design for a Combined Folding Doll House and Yard, of which the following is a specification, reference being had to the accompanying drawings, forming part thereof.

Figure 1 is a perspective view of the combined doll house and yard, unfolded, and Figure 2 is an end elevation of the same.

The front of the house, shown with the door and two windows in Figure 1, is identical with the back at the opposite side of the house.

I claim:

The ornamental design for a combined folding doll house and yard, as shown and described.

Signed at Seattle, King County, Washington, this 21st day of September, 1934.

ELLSWORTH E. SAXTON.
